(No Model.)

J. J. FINNEY.

AUTOMATIC FLUID PRESSURE BRAKE.

No. 595,706.

Patented Dec. 21, 1897.

UNITED STATES PATENT OFFICE.

JAMES J. FINNEY, OF CHICAGO, ILLINOIS, ASSIGNOR TO JOSEPH H. CHANDLER,
OF SAME PLACE.

AUTOMATIC FLUID-PRESSURE BRAKE.

SPECIFICATION forming part of Letters Patent No. 595,706, dated December 21, 1897.

Application filed April 27, 1896. Serial No. 589,225. (No model.)

To all whom it may concern:

Be it known that I, JAMES J. FINNEY, a citizen of the United States, residing at Chicago, in the county of Cook and State of Illinois, have invented certain new and useful Improvements in Automatic Fluid-Pressure Brakes, of which the following is a full, clear, and exact specification.

My invention relates to the quick-acting valve mechanism usually employed in connection with or adjacent to the triple valve for causing free or abnormal exhaust of train-pipe pressure at each triple valve, whereby the passage between the brake-cylinder and auxiliary reservoir is opened to its maximum capacity and the brakes instantly applied with full force; and my invention is designed as an improvement on the principle of that class of said devices such as is shown in my United States Patent No. 547,484, issued October 8, 1895, in which the pressure is exhausted directly into the atmosphere as contradistinguished from those which exhaust from the train-pipe into the brake-cylinder. In my said prior device the emergency exhaust-valve (the valve which opens in the vicinity of each triple valve for permitting abnormal exhaust or reduction of train-pipe pressure) is normally open to the atmosphere, but the untimely venting of the train-pipe pressure therethrough is prevented by the main slide-valve, which cuts off communication between the emergency exhaust-port and the train-pipe until the engineer's valve has been turned to the position of emergency application, which induces the main abutment or piston to shift the main slide-valve to a position which brings about exhaust directly from the train-pipe into the atmosphere through the emergency-valve and also effects the closing of the emergency-valve by the train-pipe pressure as the latter is again raised.

My present invention operates on a principle which is substantially the reverse of this; and it has for its primary object to open the emergency exhaust-valve directly to the atmosphere independently of the triple valve by pressure accumulated from the train-pipe and preponderating over the latter when abnormal reduction in the train-pipe is ex-

hausted for the purpose of emergency application and to close such emergency-valve or to control the closing thereof by permitting the said opening-pressure behind it to exhaust, thereby holding the emergency exhaust-port open until sufficient train-pipe reduction has taken place to effect the actuation of the triple valves to the emergency-application position independently of any movement as a condition precedent on the part of the triple valve or its piston.

My invention also has for its object to improve the construction of the valve mechanism of fluid-pressure brakes, whereby the same is simplified and rendered more durable.

With these ends in view my invention consists in certain features of novelty in the construction, combination, and arrangement of parts by which the said objects and certain other objects hereinafter appearing are accomplished, all as fully explained with reference to the accompanying drawings and more particularly pointed out in the claims.

In the said drawings, Figure 1 is a vertical sectional view of my improved valve mechanism, showing the parts in "release" position. Fig. 2 is a transverse sectional view taken on the line 2 2, Fig. 1; and Fig. 3 is a plan view of the slide-valve.

In carrying out my invention I expose or subject the emergency exhaust-valve to train-pipe pressure on both sides, so that under normal conditions this valve will be balanced by such pressure, the difference in pressure occasioned in the train-pipe by service stops being compensated for by providing the valve with differential areas, the larger area being on the side next the train-pipe, or by subjecting it on such side to the action of a spring of sufficient tension to cause a pressure approximately equal to the reduction in the train-pipe produced by service application, the preponderance of pressure of course being preferably toward the valve-seat, so as to prevent leakage under normal conditions, and to accomplish this I store up pressure on one side of the emergency exhaust-valve from the train-pipe in some suitable chamber or passage, which is preferably normally open to the train-pipe pressure, but which normally exerts a tendency against the emergency ex-

haust-valve for forcing the latter from its seat as soon as the train-pipe pressure has been abnormally reduced.

In an application filed contemporaneously herewith and which contains the generic claims to my invention, of which the form shown herein is a species, I have shown an arrangement by which the emergency exhaust-valve is unseated by train-pipe pressure communicating therewith at a point between the triple-valve piston and the auxiliary reservoir; but in the present form of my invention the train-pipe pressure for unseating the emergency-valve is stored up in a separate or independent reservoir or chamber which has no direct connection with the triple-valve chamber or with the auxiliary reservoir, but which is in permanent communication directly with the train-pipe.

1 represents the triple-valve casing, having the piston-chamber 2, containing the main piston or abutment 3 and communicating with the train-pipe 4. 5 represents the passage which leads from the auxiliary reservoir into the slide-valve chamber 6, containing the slide-valve 7, and 8 is the passage which leads to the brake-cylinder and communicates with the slide-valve chamber 6 and brake-port 9, formed through the valve-seat of the bushing 10. 11 represents the exhaust-port in said bushing 10, which is placed in communication with the brake-port 9 when the parts are in the release position by means of the usual valve-cavity 12, formed in the slide-valve 7, the exhaust-port 11 being in communication with a passage 13, formed around the bushing 10 and communicating with the outlet-port 14, as shown in Fig. 2. All of these parts may be of the usual or any suitable construction.

The triple-valve casing 1 is provided with a special chamber 15, which is preferably formed integrally therewith and which constitutes the aforesaid chamber for storing pressure from the train-pipe for use in opening the emergency exhaust-valve 16. Below the chamber 15 is formed a chamber 17, which accommodates the valve 16 and also constitutes a drip-chamber, and which is closed at the bottom by a screw-cap 18 of sufficient size to permit the valve 16 to be inserted through the bottom opening closed thereby. The chamber 15 is provided with an opening into the chamber 17, and consequently into the train-pipe; but this opening is closed by the upper end of the valve 16, which is in the form of a piston 19 and which is continually exposed to the pressure in the chamber 15. The other or under side of the valve 16 is provided with a conical enlargement 20, which closes one or more exhaust-ports 21, leading directly into the atmosphere from the train-pipe. Interposed between the screw-cap 18 and the under side of the valve 16 is a spring 22, which exerts a normal tendency to force the valve 16 to its seat and close the ports 21. This spring preferably surrounds a stem 23,

formed on the under side of the valve, and is housed within a sleeve 24, formed on the upper side of the cap 18. By this means the tension of the spring may be adjusted.

When the parts are in the release position, as shown in Fig. 1, and the train-pipe is feeding into the auxiliary reservoir through the feed-passage 25, the train-pipe pressure also enters the chamber 15 through a by-pass passage which is preferably formed directly through the valve 16, as shown at 26, and which is of such small capacity or area as to prevent the pressure in the chamber 15 instantly seeking equilibrium within the pressure in the train-pipe should the latter be suddenly reduced, and consequently in the event of such reduction in the train-pipe the tendency of the pressure in the chamber 15 is to unseat the valve 16 and throw open the emergency exhaust-valve 21; but in order that the reduction in the train-pipe occasioned by service application of the brakes may not have this effect on the valve 16 the spring 22 is provided; but it is quite evident that the same result might be accomplished, and, in fact, is accomplished to a degree by the differential areas of the valve 16, the larger area being exposed directly to the train-pipe pressure, while the smaller area or piston 19 is exposed to indirect pressure through the by-pass 26. When this reduction for service application of the brakes occurs, the piston 3 shifts the slide-valve 7 and brings the service-application port 27 into coincidence with the brake-cylinder port 9, the valve 16 remaining in the position shown in Fig. 1; but should the engineer's valve be thrown to a position of emergency application, causing an abnormal reduction in the train-pipe, the sudden rush of the pressure in the chamber 15 to equalize with the reduced pressure in the train-pipe will unseat the valve 16 because of the incapacity of the by-pass 26 to permit of the exhaustion of the contents of the chamber 15 as rapidly as the exhaustion takes place in the train-pipe, and consequently the train-pipe is thrown open through the exhaust-port 21 directly to the atmosphere, and sufficient exhaust is caused in the vicinity of each triple valve to induce the pistons thereof to pull the slide-valves back entirely from over the brake-cylinder port 9 and permit the pressure to enter the brake-cylinder to the full capacity of such port 9. The emergency exhaust-valve 16 remains open, permitting exhaust from the train-pipe directly into the atmosphere until sufficient pressure has escaped from the chamber 15 through the by-pass 26 to establish equilibrium or approximate equilibrium between the chamber 15 and the train-pipe, whereupon the pressure of the spring 22, if not that of the increasing train-pipe pressure, forces the valve 16 to its seat and prevents complete exhaustion from the train-pipe.

In the use of air-brake systems considerable annoyance is caused by the accumulation of

waters of condensation in the train-pipe and other passages in the system, and for the relief of this special drain-cocks are provided at intervals; but these, beyond being objectionable because of their non-automatic character, are often broken off and rendered inoperative by incompetent or careless attendants. With my drip-chamber 17, arranged, as shown, at a point below the train-pipe, the 5 waters of condensation will be collected therein, and when the emergency-valve 16 is thrown open such water will be expelled through the exhaust-ports 21, which are also below the level of the train-pipe, by first the downward 10 and then the upward rush of air, and this operation may be performed by the engineer at any other time, thus clearing out the entire system by one and the same operation of the engineer's valve.

15 In my said prior application I have also shown, described, and claimed certain improvements in the slide-valve mechanism, which I will now explain. The slide-valve 7 is provided with a transverse mortise 28, in 20 which is located a cup or yoke 29, formed on one end of the piston-stem 30, while the end of the slide-valve is provided with a longitudinal mortise 31, into which the piston-stem 30 is dropped. The graduating-valve 32 has 25 its end located in said cup or yoke 29 and is loosely connected therewith by a pin 33, passing through such yoke and the usual slot in the valve 32. By this means the piston-stem is loosely connected to both the slide-valve 7 and the graduating-valve 32, and such connections are independent of each other, whereby the strain on the pin 33 resulting from the 30 friction of the valve 7 is avoided.

Having thus described my invention, what 40 I claim as new, and desire to secure by Letters Patent, is—

1. A valve mechanism for fluid-pressure brakes having in combination a train-pipe, an air-storing chamber independent of and 45 disconnected with the triple-valve mechanism, a passage leading into said chamber from

said train-pipe, a piston fitting in and closing said passage and having a laterally-projecting conical flange constituting a valve, and a valve-seat surrounding said passage and having exhaust-ports formed therein and adapted to be closed by said conical flange, said chamber having a restricted by-pass passage comprising its sole ingress and egress whereby the pressure in said chamber will unseat said valve, and said valve and piston being provided with means for returning them to their normal position, substantially as set forth. 55

2. A valve mechanism for fluid-pressure brakes having in combination a train-pipe, 60 an emergency exhaust-valve for discharging directly from the train-pipe, a piston for controlling said valve, said valve and piston being subjected on opposite sides to direct and indirect train-pipe pressure, and an atmospheric exhaust-port closed by said valve and being located below the level of the train-pipe, whereby when the valve is opened by an excessive reduction of pressure in the train-pipe, the train-pipe will be drained of the 65 waters of condensation, substantially as set forth.

3. A valve mechanism for fluid-pressure brakes, having in combination a train-pipe, an air-storing chamber independent of and 70 disconnected with the triple-valve mechanism, a passage leading into said chamber from the train-pipe, a piston fitting in and closing said passage and having a laterally-projecting conical flange constituting a valve, a 75 valve-seat surrounding said passage and having exhaust-ports formed therein and adapted to be closed by said conical valve, said chamber being closed save for a restricted by-pass passage whereby the pressure therein will unseat said valve, and a spring for seating said valve, substantially as set forth. 80

JAMES J. FINNEY.
